VACUUM TUBE

William W. Eitel, San Bruno, Calif., assignor to
 Eitel-McCullough, Inc., San Bruno, Calif., a
 corporation of California

Application January 17, 1944, Serial No. 518,643

4 Claims. (Cl. 250—27.5)

My invention relates to vacuum tube structure, and more particularly to improvements in the internal electrodes thereof.

When vacuum tubes are in certain kinds of service they are subjected to vibration and shock which is prone to cause breakage of fragile internal elements such as the filament. In tubes wherein the cathode and grid electrodes are free at one end, which type of structure has numerous advantages from the standpoint of manufacture, there is special danger of filament breakage due to relative vibration between the electrodes.

It is among the objects of my invention to provide a tube of the character described having an electrode construction designed to resist filament breakage.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a fragmentary view, partly in section and partly in elevation, showing a tube embodying the improvements of my invention; and

Figure 2 is an enlarged top view of the grid and center rod.

Figure 3 is an enlarged fragmentary side view of the upper portions of the grid and filament structures, showing a modified arrangement.

In terms of broad inclusion, my tube comprises an envelope, a pair of concentric electrodes in the envelope each having an upper free end and a lower terminal end. One of these electrodes includes a fragile element such as a filament strand. Supporting means is provided in the envelope connected to the terminal ends of the electrodes, and means is provided adjacent the free ends of the electrodes to prevent contact of the fragile element with the other electrode upon vibration thereof.

In greater detail, and referring to Figures 1 and 2 of the drawing, my tube comprises an envelope 2 of vitreous material such as glass having a reentrant stem 3 with an exhaust tubulation 4. A pair of concentric electrodes including a cathode 6 and grid 7 are provided in the envelope. The usual plate structure, which may be suspended from the upper portions of the envelope, is not shown because my improvements are sufficiently illustrated by the two electrodes shown.

The cathode has a center rod 8 sealed to stem

3. Filament wires 9 extend longitudinally of the center rod and are hairpin-shaped with the upper bights clamped between top disks 11. These disks are apertured to slide along rod 8. The lower terminal ends of the filaments are welded to supporting brackets 12 secured to the upper ends of leads 13 sealed to stem 3.

Connection to leads 13 is made through flexible conductors 14 when the tube is based. A metallic shield 16 capping stem 3 protects the latter against heat and electron bombardment. Tension is applied to the filaments by a sleeve 17 encircling center rod 8 and interposed between a top disk 11 and spring 18 which rests on a stop 19 secured to the rod.

Grid 7 is of the cage type having vertical bars reinforced by a wire spiral. The lower end of the grid terminates in a base ring 21 supported by a bracket 22 secured to a lead 23 sealed to the side of the envelope. The upper end of the grid is free as in the upper end of the cathode structure. This free-ended feature of the electrodes has many advantages, particularly in assembling the tube. The disadvantage however is that the upper ends are subject of vibration when the tube is jarred. This is apt to cause breakage of the fragile filament when it hits the grid. Much filament breakage is traceable to this cause.

My solution to the problem is to provide means adjacent the free ends of the electrodes to prevent contact of the filament with the grid upon vibration thereof. This is accomplished in Figures 1 and 2 by projecting center rod 8 up through an aperture 24 in the top 26 of the grid, the spacing between the rod and rim of the aperture being less than the distance between the filament wires and the grid. Under excessive vibration or shock the center rod will be the first to strike the grid, thus protecting the fragile filament wires.

In the modification shown in Figure 2 a laterally projecting stop or disk 27 is provided on the upper end of the center rod within the grid, the spacing between the edge of the disk and grid being less than that between the filament wires and grid.

I claim:

1. A tube comprising an envelope, a pair of concentric electrodes in the envelope each having an upper free end and a lower terminal end, one of said electrodes including a fragile element, electrode supporting means in the envelope connected to said terminal ends, and means adjacent the free ends of the electrodes and normally spaced freely from at least one of said electrodes

to prevent contact of said fragile element with the other electrode upon vibration thereof.

2. A tube comprising an envelope, a cathode center rod having an upper free end and a lower end fixed to the envelope, a filament wire extending alongside the center rod and held at its upper end by said rod, a cathode lead projecting into the envelope and connected to the lower end of said wire, a grid mounted in the envelope and disposed about the filament wire, and means co-acting with the center rod and normally spaced freely from the grid to prevent contact of said filament wire with the grid upon vibration thereof.

3. A tube comprising an envelope, a cathode center rod having an upper free end and a lower end fixed to the envelope, a filament wire extending alongside the center rod and held at its upper end by said rod, a cathode lead projecting into the envelope and connected to the lower end of

said wire, a grid mounted in the envelope and disposed about the filament wire, and a top on the grid having an aperture through which the center rod projects, said rod being normally spaced freely from the rim of the aperture a distance less than the distance between said filament wire and the grid.

4. A tube comprising an envelope, a cathode center rod having an upper free end and a lower end fixed to the envelope, a filament wire extending alongside the center rod and held at its upper end by said rod, a cathode lead projecting into the envelope and connected to the lower end of said wire, a grid mounted in the envelope and disposed about the filament wire, and a laterally projecting stop on the center rod within the space enclosed by the grid, said stop being spaced from the grid a distance less than that between the filament wire and the grid.
